UNITED STATES PATENT OFFICE.

JOSEPH BECK AND ALBERT E. GALLIN, OF TAFT, CALIFORNIA.

MOTOR-DRIVEN SAW.

Application filed February 11, 1926. Serial No. 87,619.

This invention relates to improvements in power driven saws.

An object of this invention is to provide a saw of improved construction which is driven by means of a motor and which is readily portable from place to place so that it can be used for many different purposes.

Another object of this invention is to provide an improved saw consisting essentially of a frame, a motor mounted on the frame, a saw, and an improved construction connecting the motor to the saw so that the saw can be reciprocated by the motor relatively to the frame.

15 A further object of this invention is to provide a saw having the above mentioned characteristics and which has a handle with which is associated a switch which controls the circuit through the electric motor which 20 operates the saw.

A further object of this invention is to provide a power driven saw having a handle at one end and a motor upon the other end, so that the weight of the motor will bear 25 down upon the saw.

A still further object of this invention is to provide a power driven saw having a cable extending over a pulley suspended from a ceiling and a counterweight upon the other 30 end of the cable, so that the saw mechanism will be supported by the counterweight to the desired extent.

With the foregoing and other objects in view which will be made manifest in the 35 following detailed description and specifically pointed out in the appended claims, reference is had to the accompanying drawings for an illustrative embodiment of the invention, wherein:

40 Figure 1 is a side elevation of the improved power driven saw, parts being broken away and shown in vertical section,

Fig. 2 is a top plan view of the same,

Fig. 3 is a view taken substantially on the 45 line 3-3 of Fig. 1,

Fig. 4 is a view taken substantially on the line 4-4 of Fig. 1,

Fig. 5 is a horizontal section taken on the line 5-5 of Fig. 1,

50 Fig. 6 is a view in elevation, parts being broken away and shown in section, illustrating a detail of construction, and

Fig. 7 is a sectional view taken on the line 7-7 of Fig. 6.

55 Referring to the accompanying drawings wherein similar reference characters design-

nate similar parts throughout, the improved saw consists of a frame having front and rear uprights 10 and 11, which are connected at their upper ends by means of a cross bar 60 12. In the lower ends of the uprights 10 and 11 there are formed bores 13 and 13^a, and a tubular part 14 may be formed integral with the forward upright 10 which has its interior in alignment with the bore 13 65 of the upright 10. Guide members 15 and 16 are slideable in each of the bores 13 13^a and also in the tubular part 14. A saw blade 17 has its ends detachably connected to the guide members 15 and 16 so that one saw 70 blade can be replaced by another. On the forward side of the upright 10 there is positioned a triangular plate 18, this plate being either formed integral with the upright 10 or being attached thereto as by welding. 75

It carries lateral base flanges 19. Two divergent angle members 20 are secured to the opposite sides of the upright 10 and to the under side of the base flanges 19 and project forwardly therefrom. In a similar manner a 80 pair of divergent angle irons 21 are welded or otherwise secured to the lower end of the upright 10 and extend forwardly therefrom. See Fig. 5. The forward ends of each of the angle members 20 are connected to the forward ends of their respective angle irons 21 by vertical braces 22, and similar braces 23 connect the angle irons intermediate their ends. The forward ends of the angle irons 20 are connected to each other by means of 85 a horizontal brace 24 and in a like manner the forward ends of the angle irons 21 are connected by a brace 25.

On top of the upper angle irons 20 there is mounted an electric motor 26, the rotor shaft of which is illustrated as being provided with a pinion 27. The rotor shaft extends through a plate 28 which is secured to the forward ends of the angle irons 20 and 21 as by angles 29, this plate forming 90 the back wall of a gear case or housing. The other walls of the gear case or housing are provided by a cover 30 which is detachably secured to the plate 28. A column 31 connects the upper and lower braces 24 and 25 100 and provides a bearing for a small shaft 32 carrying a gear 33 which meshes with the pinion 27. The shaft 32 also carries a beveled pinion 34 which meshes with the beveled gear 35 mounted on a shaft 36 which 105 is rotatable upon a support 37 mounted on one of the lower angle irons 21. The beveled 110

gear 35 carries a crank pin 38 for an eccentric rod, generally indicated at 39. This eccentric rod consists of two end members into which is threaded the ends of a rod 40, the rod being locked as by lock nuts 41, so that an adjustment of the length of the eccentric rod is permissible. The other end of the eccentric rod 39 is pivotally connected to an arm 42, which is slidable in a slot 10 formed in the top of the tubular part 14. The guide member 16 is connected to a tension spring 43, which in turn is connected to an adjusting screw 44 mounted on a spring housing 45.

15 The operation of the above described construction is as follows: When the motor 26 is rotating, the pinion 27 drives the gear 33, which in turn causes the beveled pinion 34 to drive the beveled gear 35. This operates 20 the eccentric rod 39 and causes the guide member 15 to reciprocate, thus reciprocating the saw blade 17 and the guide member 16. The tension spring 43 serves to maintain the saw blade 17 under tension during the reciprocation. In this manner it will be understood that the frame may be positioned so 25 that the saw blade is contacting with the work to be cut, and by holding the frame stationary, the electric motor 26 will cause 30 the blade 17 to reciprocate and to saw. Obviously, other types of constructions may be employed for causing the motor 26 to reciprocate the saw blade 17, if so desired.

On the upright 11 there is provided a handle 46 and a movable member 47 has guide pins 48 slideable in recesses formed in the handle. The movable member 47 is urged outwardly into engagement with the stop 49 by means of coil springs 50 disposed about 35 the pins 48. In the handle there is positioned a contact 51 which is engageable by a movable contact 52 on the movable member 47. The stationary contact 51 may be connected by means of a wire 53 to a source of 40 electric current and the movable contact 52 is in a like manner connected to the motor 26, the other terminal of the motor being connected to the source of supply. In this 45 manner the switch on the handle 46 controls 50 the circuit through the electric motor 26.

As the saw of this construction is fairly heavy, it is desirable to mount a screw-eye 54 on the frame which may be located at the point where the upright 10 is joined to the 55 cross bar 12. A cable or similar supporting member 55 can be connected to the screw-eye

54 and be suspended from the ceiling. If desired, this cable 55 may pass over pulleys 55^a and 55^b and have its opposite end connected to a balance weight 55^c, and in this manner the saw may be supported. It is also desirable that a plug 56 be provided upon the screw-eye, to which an electric light socket 56^a may be attached, this plug serving to provide contacts enabling the electric current to be conveyed to the motor 26 and to the stationary contact 51.

60 The plug 56 is secured to the screw-eye 54 to receive the socket 56^a upon the extension cord 56^b, this extension cord being attached to the light service wiring as is usual with extension cords. Of course, if desired, the plug may be on the end of the cord and the socket upon the screw-eye 54.

65 From the above described construction it will be readily appreciated that a power driven saw of an improved nature has been provided, which is quite portable and which has many advantages.

70 It will be understood that various changes in the detail of construction may be made without departing from the spirit or scope of the invention as defined by the appended claim.

75 We claim:

A motor driven saw comprising in combination a pair of uprights connected at one end by a cross bar, guiding means in the lower ends of said uprights, guide members slideable in said guiding means and a saw 80 connected to said guide members, an electric motor mounted on one of said uprights, means connecting said motor to one of said guide members to reciprocate the same and reciprocate the saw, a handle associated with 85 the other upright at the other end of the frame from said electric motor, said handle comprising a U-shaped member, wells in said U-shaped member, a pressure member extending parallel to one side of said U-shaped member and having pins receivable in said wells, springs surrounding said pins to normally urge said pressure member away from 90 said handle member, and means whereby pressure upon said handle and the consequent urging of said pressure member toward 95 said handle will cause an electrical circuit to operate said motor.

100 In testimony whereof we have signed our names to this specification.

JOSEPH BECK.
ALBERT E. GALLIN.
